(57) **CLAIM**

The ornamental design for a combined personal digital assistant and navigation device, as shown and described.

DESCRIPTION

FIG. 1 is a front perspective view of a combined personal digital assistant and navigation device according to the present invention;

FIG. 2 is a rear perspective view thereof;

FIG. 3 is a front elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear elevational view thereof.
